UNITED STATES PATENT OFFICE.

GEORGE E. BLAINE, OF INDIANAPOLIS, INDIANA.

RAILWAY-RAIL FASTENER.

No. 868,836.

Specification of Letters Patent.

Patented Oct. 22, 1907.

Application filed May 2, 1907. Serial No. 371,444.

To all whom it may concern:

Be it known that I, GEORGE E. BLAINE, a citizen of the United States, residing at Indianapolis, in the county of Marion and State of Indiana, have invented 5 certain new and useful Improvements in Railway-Rail Fasteners; and I do declare the following to be a full, clear, and exact description of the invention, such as will enable others skilled in the art to which it appertains to make and use the same.

10 This invention relates to an improved railway rail fastener.

The object of the invention is to provide a device for securing the rails to ties, without the use of spikes, and which is arranged to prevent wear of the ties.

15 Another object is to provide a combined rail fastener and rail brace.

In the accompanying drawings.—Figure 1 represents a side elevation of this improved rail fastener applied, the rail being shown in section; Fig. 2 represents a top 20 plan view thereof, with parts broken out; Fig. 3 represents a side elevation of the rails with the fastener applied thereto shown in end elevation; Fig. 4 represents a transverse section of a modified form of fastener applied; and Fig. 5 represents a perspective view of 25 the adjusting bolt detached.

In the embodiment illustrated, a T-shaped tie plate is shown, the stem or vertical member 2 of which is cut out at 3 to form a rail-receiving recess, and said plate has corrugations 4 extending transversely thereof between the spaced members of the stem 2 and on opposite sides thereof to strengthen the plate and prevent bending thereof when heavy loads pass thereover. This plate is secured to the ties, preferably by lag-screws, as 5.

35 In the form shown in Figs. 1, 2 and 3, the stems 2 have bolt holes 6 extending therethrough, and have mounted thereon laterally-adjustable rail fasteners 10. These fasteners are preferably made U-shaped, as shown, and the opposite sides or legs 11 thereof have 40 longitudinally-arranged, outwardly-flaring slots, as 12, through which and in the holes 6 in the stems 2 project bolts 13 having tapered heads 14. These bolts when the nuts are screwed thereon force the fasteners forward until the cut-out portions 15 fit over the base of 45 the rail 20. One of the fasteners 10 is provided with a rail brace in the form of an upwardly-extending arm

16, with the free end thereof shaped to fit under the tread of the rail, as shown in Fig. 1.

The rail fasteners may both be made adjustable, as shown in Figs. 1 and 2, or only one may be made adjustable and the other fixed, as shown in Fig. 4, and they may be made with or without rail braces as desired.

I claim,—

1. A railway rail fastener comprising a T-shaped plate 55 having the upwardly-extending stem thereof cut out to form a rail-receiving recess, and laterally movable means carried by said stem for engaging the rail and locking it to the plate.

2. A railway rail fastener comprising a T-shaped plate 60 having the upwardly-projecting stem thereof cut out to form a rail-receiving recess, and a laterally-movable member for engaging the rail, and means for locking said member to the plate.

3. A railway rail fastener comprising a T-shaped plate 65 having the upwardly-projecting stem thereof cut out to form a rail-receiving recess, a laterally-movable, rail-engaging member mounted to slide on said stem, and means for locking said member to said stem.

4. A railway rail fastener comprising a T-shaped plate 70 adapted to be secured to the ties and having the upwardly-projecting stem thereof cut out to form a rail-receiving recess and provided with corrugations extending transversely thereof between the spaced members of the stem on opposite sides thereof, and means connected with said 75 plate for securing a rail thereto.

5. A railway rail fastener comprising a T-shaped plate having the upwardly-projecting stem thereof cut out to form a rail-receiving recess, a laterally-slidable hood mounted on said stem and having means for engaging a 80 rail, and means for moving said hood inwardly.

6. A railway rail fastener comprising a T-shaped plate having the upwardly-projecting stem thereof cut out to form a rail-receiving recess and an approximately 85 U-shaped hood sliding on said stem, and means for moving said hood inward and locking it in adjusted position.

7. A railway rail fastener comprising a T-shaped plate having the upwardly-projecting stem thereof cut out to form a rail-receiving recess and an approximately 90 U-shaped hood sliding on said stem, means for moving said hood inward and locking it in adjusted position, and an upwardly-inclined arm extending from the inner end of said hood and adapted to engage a rail and form a brace therefor.

In testimony whereof I have hereunto set my hand in 95 presence of two subscribing witnesses,

GEORGE E. BLAINE.

Witnesses:

W. A. JOHNSON,
A. C. PURPLE.
